ERNEST LARBALESTER, OF FORT WILLIAM, ONTARIO, CANADA, ASSIGNOR TO FORT WILLIAM PAPER CO., LIMITED, OF FORT WILLIAM, PROVINCE OF ONTARIO, CANADA.

CORE-TIP-TRUING MACHINE.

Application filed November 5, 1925. Serial No. 67,070.

It is common in the paper making industry to employ tubular paper cores which are provided with annular sheet metal tips of U-section which frequently require to be removed and trued up for reuse and this invention has relation to certain new and useful improvements in a core tip truing machine and has for its primary object the provision of a machine of simple construction which will be highly efficient in the straightening and truing of core tips such as referred to.

With the foregoing and other objects in view, as will appear as the description proceeds, the invention consists of the novel construction, combination and arrangement of co-operating elements as hereinafter more specifically set forth and illustrated in the accompanying drawings forming a part of the present application and which may be briefly described as follows:

Fig. 1 is a front elevation of the machine showing it at the top of the stroke of the actuating mechanism.

Fig. 2 is a side elevation of the machine showing it at the top of the stroke of the actuating mechanism.

Fig. 3 is a vertical transverse section through the machine, substantially on the plane of the line 3—3 of Fig. 2, looking in the direction indicated by the arrows and showing a core tip in position in the truing device with the actuating mechanism at the bottom of its stroke.

Referring more in detail to the drawings in which similar reference characters designate corresponding parts throughout the several views, it will be noted that the machine includes:

A supporting frame structure 10 on which are attached the cylinder 11 of the actuating mechanism by means of the bracket 34 and the annular bottom die 12 of the truing device by means of the lugs 35 as shown in Figs. 1 and 2. The top die 14 of the truing device is connected to and actuated by the piston 15 by means of the piston rod 16. This top die is formed with an annular groove to fit over a core tip as shown.

The cylinder 11 is made air-tight or fluid-tight by means of the stuffing boxes 17 and 18. The piston 15 is secured to the piston rod 16 by means of the nut 19 or other mechanical contrivance and is actuated by air

or other fluid admitted into cylinder 11 through either pipes 20 or 21 as desired. The admission of air into the pipes 20 and 21 is controlled by the four way valve 22, or some other equivalent mechanism, from the feed pipe 32 and is exhausted by way of the pipe 33. To the upper die is secured a stop bar 27, through which pass the rods 23 which are secured to the cross bar 25 which is movable in slots in the side of the annular bottom die and supports the stripping member 13. Nuts 28 are threaded on the upper ends of the rods and shoulders 24 are provided on the rods below the stop bar.

Considering now the mechanism with the piston 15 at its top position as shown in Fig. 2: The core tip is placed on the annular bottom die 12. The valve 22 is now opened and the piston 15 is actuated downwards, this motion allowing the rods 23 to also move downwards carrying with them the stripping block 13 which is supported by the bar 25. When the top die 14 has moved down sufficiently it begins to force the core tip 26 over the bottom die 12 until the dies and tip take up the relative positions shown in Fig. 3. In this, the bottom position of the mechanism, the piston is not allowed to move farther downwards since the stop bar 27 rests against the shoulders 24 of the rods 23.

Now, again, on the upstroke of the piston 15, controlled by the valve 22, the core tip 26 strips off in one of two ways, it either remains in the top die 14 or on the bottom die 12. If the core tip remains on the bottom die 12 when the stop bar 27 strikes the nuts 28 of the rods 23, the rods 23 and hence the bar 25 are impelled upwards in the slot 31. This motion of the bar 25 moves the stripping block 13 upwards and this action strips the core tip 26, the block 13 returning to its original position as shown in Fig. 2, when the dies are again brought together.

On the other hand if the core tip stays in the top die 14, it remains there until the die 14 has moved up sufficiently for stripping pins 29 to come into action. These stripping pins 29 are stationary pins secured to the cap 32 threaded on the neck of the stuffing box 18 of the cylinder and guided by guide tubes 30 secured to the upper die 14 about the openings left in the die to receive them. As the die 14 moves upward,

the stripping pins 29 come into action and completely eject the core tip. The die 14 finally comes to rest in position as shown in Fig. 2 when the guide tubes 30 are stopped 5 by striking against the cap 32 or some other stopping device.

The stripping block 13 is recessed and drilled to allow dirt, etc., which might collect from the core tips, to escape, so that it 10 can not build up a pressure or jam any of the working parts. The piston 15 is so constructed that the packing pieces 36 make it fluid tight within the cylinder.

It is believed the complete construction 15 and operation of the machine will now be understood from the foregoing description taken in conjunction with the accompanying drawings. The construction and operation of the machine as designed assures 20 quick and proper straightening and truing of the core tips and at a considerable saving of time, energy and expense over the slow and expensive practice of straightening and truing the core tips by hand as heretofore 25 followed.

While the preferred embodiment of the invention has been disclosed it is to be understood that minor changes in the details of construction, combination, arrangement of 30 co-operating elements, and actuating fluids or materials may be resorted to within the scope of what is claimed, without departing from the spirit of the invention and more particularly in regard to the construction of 35 the supporting frame structure 10 and of the method employed in connecting the cylinder 11 and bottom die 12 to the aforesaid frame structure.

What I claim is:

40 1. Core-tip straightening and truing mechanism comprising a male die of annular form adapted to enter the channel of a core tip; a female die grooved to fit over the core tip; means for reciprocating one die relative to the other; a stripping member movable longitudinally of the male die; stripper pins secured to a stationary part adapted to operate through the bottom of the female die; positive connections whereby the separation of the dies will actuate the stripping member, lost motion being provided in such connections and the stripper pins so located that neither of the stripping means operatively engages the core tip until the dies are 45 sufficiently separated for the removal of a core tip from between them.

60 2. Core-tip straightening and truing mechanism comprising a bottom annular die adapted to enter the channel of a core tip; a top die grooved to fit over the core tip; means for reciprocating one die relative to the other; means for stripping a tip from the bottom die comprising a stripping member movable longitudinally of the annular die; a cross-bar adapted to move said strip- 65

ping member; and connecting means between the cross-bar and the top die adapted to lift the cross-bar when the dies are separated.

3. Core-tip straightening and truing mechanism comprising a bottom annular die 70 adapted to enter the channel of a core tip; a top die grooved to fit over the core tip; means for reciprocating one die relative to the other; means for stripping a tip from the bottom die comprising a stripping member movable longitudinally of the annular die; a cross-bar adapted to move said stripping member; and connecting means between the cross-bar and the top die adapted to lift the cross-bar when the dies are separated, including provision for lost motion.

4. Core-tip straightening and truing mechanism comprising a bottom annular die 75 adapted to enter the channel of a core tip; a top die grooved to fit over the core tip; means for reciprocating one die relative to the other; means for stripping a tip from the bottom die comprising a stripping member movable longitudinally of the annular die; a cross-bar adapted to move said stripping member; rods secured to the cross-bar; a stop bar connected to the top die provided with openings through which the rods pass; stop shoulders on the rods engageable by the stop bar to limit the movement of the dies towards one another; and shoulders engageable by the stop bar to move the cross-bar and stripper when the dies are moved apart.

5. Core-tip straightening and truing 100 mechanism comprising a bottom annular die adapted to enter the channel of a core tip; a top die grooved to fit over the core tip; a piston rod to which the top die is connected; a piston to which the piston rod is connected; a cylinder for said piston; a stripping member movable longitudinally of the annular die; a cross-bar adapted to move said stripping member, the wall of the annular die being slotted to permit of 105 the necessary movement of the bar longitudinally of the die; rods secured to the cross-bar; a stop bar connected to the top die provided with openings through which the rods pass; stop shoulders on the rods engageable by the stop bar to limit the movement of the dies towards one another; and shoulders engageable by the stop bar to move the cross-bar and stripper when the dies are moved apart.

6. Core-tip straightening and truing 110 mechanism comprising a bottom annular die adapted to enter the channel of a core tip; a top die grooved to fit over the core tip; a piston rod to which the top die is 115 connected; a piston to which the piston rod is connected; a cylinder for said piston; a stripping member movable longitudinally of the annular die; a cross-bar adapted to move said stripping member, the wall of 120

the annular die being slotted to permit of the necessary movement of the bar longitudinally of the die; rods secured to the cross-bar; a stop bar connected to the top die provided with openings through which the rods pass; stop shoulders on the rods engageable by the stop bar to limit the movement of the dies towards one another; shoulders engageable by the stop bar to move the cross-bar and stripper when the dies are moved apart; and stationary stripper pins connected with the cylinder, the top die having holes therein through which the pins may operate when the two dies are moved apart.

5 a piston rod to which the top die is connected; a piston to which the piston rod is connected; a cylinder for said piston; rods secured to the cross-bar; a stop bar connected to the top die provided with openings 20 through which the rods pass; stop shoulders 25 on the rods engageable by the stop bar to limit the movement of the dies towards one another; shoulders engageable by the stop bar to move the cross-bar and stripper when the dies are moved apart; and stationary 30 stripper pins connected with the cylinder, the top die having holes therein through which the pins may operate when the two dies are moved apart.

10

15

7. Core-tip straightening and truing mechanism comprising a bottom annular die adapted to enter the channel of a core tip; a top die grooved to fit over the core tip;
